SLIP WITH POCKET

Robert B. Senderowitz, Allentown, Pa.

Application August 11, 1950, Serial No. 11,734

Term of patent 7 years

(Cl. D3—26)

To all whom it may concern:

Be it known that I, Robert B. Senderowitz, a citizen of the United States of America, residing in Allentown, county of Lehigh, and State of Pennsylvania, have invented a new, original, and ornamental Design for a Slip with Pocket, of which the following is a specification, reference being had to the accompanying drawing, forming part thereof, wherein,

I claim:

The ornamental design for a slip with pocket, substantially as shown and described.

ROBERT B. SENDEROWITZ.
